(57) **CLAIM**

The ornamental design for a valve handle, as shown and described.

DESCRIPTION

FIG. 1 is a perspective view of a valve handle showing my new design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a schematic view of the valve handle attached to a first object when in use;

FIG. 9 is a schematic view of the valve handle attached to a second object when in use;

FIG. 10 is a schematic view of the valve handle attached to a third object when in use; and,

FIG. 11 is a schematic view of the valve handle attached to a fourth object when in use.

The broken lines in FIGS. 7 to 11 are for illustrative purposes only and form no part of the claimed design.
